RAILWAY TRAFFIC CONTROLLING
APPARATUS

Howard A. Thompson, Edgewood, Pa., assignor to
The Union Switch & Signal Company, Swiss-
vale, Pa., a corporation of Pennsylvania

Application May 28, 1938, Serial No. 210,743

11 Claims. (Cl. 246—38)

My invention relates to railway traffic controlling apparatus and it has special reference to the organization of such apparatus into signalling systems of the class wherein coded trackway energy is utilized to control either or both wayside signals and train carried cab signals.

One object of my invention is to provide a new and improved form of such organization which protects against the giving of false "proceed" indications in the event of breakdown of the insulated joints which electrically separate the rails of adjacent track sections.

Another object is to make this protection an inherent part of signalling systems which use code following track relays of the single element type.

An additional object is to effect the named protection without staggering the polarities of adjacent track circuits.

A further object is to provide protection facilities which cause the wayside signal at the location of a broken down joint to go to "stop" before the guarded block becomes vacated and there to remain until the defective joint is repaired.

A still further object is to insure that should the energy leaking over a broken down joint be momentarily interrupted the named protection will automatically restore itself without producing even a temporary "proceed" indication on the part of the affected signal.

An additional object is to arrange the conductors and contacts of the protection giving circuits so that they are self checking.

Another object is to provide cooperating cut section facilities which break up cascading action of steady track circuit energy, which detect a failure of their own insulated joints where either front or back contact repeating is used, and which are immune to false controlling effects of "door bell" code in back contact coding.

A further object is to prevent the wayside signal at the entrance of a track section to which steady trackway energy is being supplied from flashing a false "approach" indication when a train enters that section.

A still added object is to accomplish the above without dispensing with any of the desirable features of continuously coded track circuit control.

In practicing my invention, I attain the above and other objects and advantages by supplementing the rail energy supply facilities at each signal location by what will be termed a "lock-out" circuit. Should the normally coded energy from

one track section leak forwardly over a defective joint into the rails of an adjacent section, this lock-out circuit becomes effective to supply steady or non-coded energy to the rear section rails. In feeding over the faulty joint, that steady energy holds the forward section track relay continuously picked up, and in consequence the associated decoding apparatus causes the controlled wayside signal to display a restrictive aspect as an indication of the faulty condition. 5

I shall describe a number of forms of railway traffic controlling apparatus embodying my invention and shall then point out the novel features thereof in claims. These illustrative embodiments are disclosed in the accompanying 10 drawings in which:

Fig. 1 is a diagrammatic representation of a stretch of railway track equipped with traffic controlling apparatus embodying my invention;

Figs. 2 and 3 show different forms of cut section facilities which may be used in conjunction with the signal location equipment of Fig. 1; 20

Fig. 4 is a representation of one of the signal location equipments of Fig. 1 modified to include a second form of control circuit for the code 25 detecting relay;

Figs. 5, 6 and 7 are similar representations showing still further forms which the referred to relay control circuit may take;

Fig. 8 is a showing of a cut section equipment 30 which codes over a back contact of the track relay;

Fig. 9 is a diagrammatic view of trackway apparatus which cooperates in the control of highway crossing signals and which allows non-coded 35 trackway energy to be used to control such signals without interfering with the "lock-out" protection against defective insulated joints; and

Fig. 10 is a showing of the repeater relays of the cut section location of Fig. 9 arranged in a 40 second manner to provide immunity to "door bell" codes.

In the several views of the drawings like reference characters designate corresponding parts. Referring first to Fig. 1, the improvements of 45 my invention are there disclosed as being incorporated in the trackway portion of a combined automatic block signalling and cab signalling system for a track 1—2 over which it will be assumed that traffic moves in the single direction indicated by the arrow, or from left to right in the diagram. Insulated rail joints 3 divide the protected stretch of this track into the customary successive sections and the rails of each 50

of these sections form a part of a track circuit of the usual character.

The particular track stretch which is represented in Fig. 1 is intended for use in a railway system employing electric propulsion and for this reason alternating current track circuit energy is used together with impedance bonds 4 of the customary form which conduct propulsion current around each pair of the insulated rail joints. As the description proceeds, however, it will become apparent that the apparatus of my invention is equally well suited for use on a steam road in which application either direct current or alternating current track circuit energy may be used. In such an application the bonds 4 would, of course, be omitted.

In Fig. 1 only two of the referred to track sections, E—Ea and Ea—F, are completely shown. Points of main signal block division involving these sections are marked by locations E and F while a subdivision of the signal block E—F is designated by location Ea.

Positioned at the entrance of each of the main signal blocks is a wayside signal S which is adapted to indicate to an approaching train the nature of the traffic conditions in the blocks immediately ahead. The particular signals which are shown by way of illustration at locations E and F are of a well-known color light type. When lighted, the three lamps G, Y and R of each respectively direct rays of green, yellow and red light into the range of vision of the engineer of an approaching train. As signal Se protects the entire block E—F, no wayside signal is provided at the cut section location Ea.

The rails of each of the referred to sections of track form a part of a track circuit to which coded alternating current train control energy normally is continuously supplied through a track transformer TT connected with the rails at the traffic leaving or exit end of the section by means of a circuit which includes the usual current limiting reactor 6. This energy is derived from any suitable source and distributed to the several locations of track section division in conventional manner, as by the aid of a transmission circuit (not shown) extending along the right-of-way. In the diagram, characters B and C designate power distributing terminals which are supplied from one such source. To facilitate explanation, it will be assumed that the alternating current energy of this source has a frequency of 100 cycles per second.

The particular signalling system shown in Fig. 1 is of the three indication variety and it makes use of track circuit energy of two different codings. These codings are produced by a code transmitter CT which interrupts the supply circuit of the associated track transformer TT a definite number of times per minute according to the traffic or other conditions ahead. In the illustrative form shown, each device CT is provided with two circuit making and breaking contacts 75 and 180 which are continuously actuated by a motor or other suitable mechanism (not shown in detail) at two different speeds. For purposes of explanation, it will be assumed that these speeds are such as respectively to provide codes of 75 and 180 energy pulses per minute.

Each of the referred to track circuits further includes the operating winding of a track relay TR which is installed at the traffic entering end of each track section and which receives operating energy from the rails thereof. Each of these track relays is of the single element code

following type and the winding thereof may be designed to respond either to direct or to alternating current. When of the alternating current type, the winding is directly connected to the rails of the associated track section in the manner represented in Figs. 1, 2, 3 and 7. When of the direct current type, this connection includes the supplemental equipment shown at 1 in each of Figs. 4, 5, 6, 8 and 9.

Typically, this equipment 1 may take the form of a resonant transformer unit which includes a transformer, capacitor, reactor and rectifier connected as shown in Fig. 4 and so proportioned as freely to pass the 100 cycle coded signal control energy which is received from the trackway and to rectify this energy before applying it to the direct current winding of the code following track relay TR. As regards operation, therefore, the direct current track relay is the full equivalent of the single element alternating current device shown at TR in Fig. 1.

As long as the winding of either of these two types of relays is deenergized, the relay contacts 8 and 10 are released and occupy the lowermost position, shown dotted. When, however, the track rails transmit coded energy to the relay, its response to the individual pulses thereof causes these contacts to pick up and occupy the uppermost positions, shown heavy, upon the occasion and for the continuance of each of these pulses.

In the illustrative automatic block signaling system of Fig. 1, energy of one or the other of the previously described 75 and 180 codings is normally fed to the track circuits at all times and this coded energy is used to control both the wayside signals S and cab signals mounted on a train which proceeds along the track 1—2. Because of the well-known character of such cab signals, no attempt has been made to disclose them in the present application.

For distinguishing code following operation on the part of the track relay TR and for selecting in accordance with the presence or absence of such operation the coding of the energy which is supplied to the rails of the track section to the rear, use is made at each wayside signal location of a pair of repeater relays FP and BP and a code detecting relay H. For aiding relay H in controlling the associated wayside signal S, a cooperating code distinguishing relay D180 also is provided at each location.

Devices FP and BP, respectively, are front contact and back contact repeaters for the track relay TR. Included in the energizing circuit of each is a contact 10 of the associated track relay and further included in that of relay BP is a contact 11 of the relay FP. Both of these circuits are shown as deriving energy from a direct current source, designated by the terminals "plus" and "minus." Each time that contact 10 of the track relay picks up in response to a pulse of trackway energy, the circuit of relay FP is completed over conductor 12. Likewise, each time that the track relay is deenergized and relay FP continues to hold its contact 11 in the picked-up position, the energizing circuit for relay BP is completed over conductors 13 and 14.

Both of the relays FP and BP are sufficiently slow releasing that they keep their contacts continuously picked up between adjacent pulses of trackway energy which the track relay TR receives during normal operation of the signalling system. These slow release characteristics are preferably provided through the use of snubbing resistors 15 and 16. Each of these resistors is 75

- bridged across the winding of the associated relay and serve to sustain the flux in the magnetic circuit of the relay for an appreciable period following each interruption of winding energizing current. The proportioning of each snubbing resistor is such that the associated relay will bridge the longest "off" period of any one of the codes to which the track relay TR normally responds.
10. It will thus be seen that as long as track relay TR is not following a code and is continuously deenergized, both of the repeater relays FP and BP likewise are continuously deenergized and their contacts occupy the released position.
15. When, however, the track relay follows either of the two codes which the transmitter CT at the opposite or exit end of the track section produces, relay FP is continuously picked up, its contact 11 sets up the circuit for relay BP and contact 10 of relay TR completes that circuit each time that it occupies its released position. Moreover, should the track relay receive steady energy and thus hold its contacts continuously picked up, relay FP becomes continuously energized and relay BP becomes continuously deenergized. Since relay BP can be energized only when relay TR is following a code, it functions as a code detecting device.

In order that the snubbing resistor 16 associated with the back contact repeater relay BP will be effective only when the companion relay FP is picked up, the snubbing circuit which includes resistor 16 is carried over contact 11 of relay FP. As long as relay FP continues to be intermittently energized, this contact completes the snubbing circuit and causes relay BP to introduce the before described delay in its contact releasing operation. When, however, relay FP is continuously deenergized, contact 11 opens the snubbing circuit for relay BP and, in that event, the delayed release characteristics are no longer effective. As a result, each release of contact 11 of relay FP is followed almost instantly by a release of the contacts of relay BP.

Relay H is a repeater of the second slow release relay BP and in the system of Fig. 1 it is arranged to perform a code detecting function. Preferably, it is a slow responding device of the ordinary "ferrule" type (wherein one leg of the magnetic circuit of the relay is passed through a section of heavy copper tubing that inductively retards changes in the flow of flux through that leg) and is controlled over a front contact 18 of the associated relay BP. When used, as shown, in a system employing one or another of two trackway codes of 75 and 180 energy pulses per minute, it is preferable to proportion this relay in a manner that its pick-up time will be not less than six-tenths second and its release time not less than one and two-tenths seconds.

As long as contact 19 of relay BP remains released, the winding of relay H is continuously deenergized and the contacts thereof are released. Each time, however, that contact 18 is picked up, current flows through the winding of relay H over a circuit extending from the positive terminal of a suitable supply source through front contact 18, conductor 19 and the winding of relay H back to the negative terminal of the supply source. If the length of this energizing period exceeds the pick-up time (assumed to be six-tenths second) for relay H, it moves its contacts to the picked-up position where it con-

tinues to hold them during the entire energizing period referred to and for the release time (assumed to be one and two-tenths second minimum) following the expiration thereof.

Control of the associated wayside signal S is effected by a contact 21 of relay H acting in co-operation with a contact 22 of the code distinguishing relay D180. Whereas code detecting relay H picks up whenever the associated track relay TR follows either of the 75 or 180 trackway codes, relay D180 is arranged to pick up only when the received code is of the 180 energy pulse per minute variety. For effecting this selective response, the energizing circuit of relay D180 includes a tuned unit J180 which receives alternating current voltage of code pulse frequency from the secondary winding of a decoding transformer DT.

In operation of the code distinguishing apparatus just described, a second contact 8 of the track relay TR pole changes a primary energizing circuit for the decoding transformer DT in the customary manner. That is, each time that the contact is picked up, direct current flows in one direction through one portion of the transformer primary (by way of a circuit which extends from the positive terminal of a suitable supply source through front contact 8, conductor 23, the upper half of the transformer winding and mid tap 4 back to the negative terminal of the supply source) and each time that contact 8 is released, current flows in the opposite direction through another portion of the winding (by way of a circuit which includes conductor 25 and the lower winding path).

The resulting alternating current voltage of code pulse frequency which is induced in the secondary winding of transformer DT supplies the winding of code distinguishing relay D180 with current of pick up intensity only if the frequency of that voltage is of the 180 code rate to which the tuned circuits of the unit J180 are resonant. Thus, relay D180 picks up its contact 22 in response to operation of relay TR which is initiated by the 180 code and maintains its contact in the released position at all other times, including those when energy of the 75 pulse per minute code rate is received from the trackway. Because of the well-known character of the circuits which make up the resonant unit J180 no detailed description thereof is here given.

From the foregoing it will be seen that as long as the track relay TR fails to respond to coded energy from the trackway, the contacts of both of the relays H and D180 will remain released. Under the stated condition (which obtains when the associated track section is occupied by a train), the controlled wayside signal S displays the indication of "stop" by virtue of lamp R thereof receiving lighting current over a circuit which may be traced from the positive terminal of a suitable supply source through back contact 21 of relay H, conductor 26 and the lamp R back to the negative terminal of the supply source.

When, however, energy of the low speed or 75 coding is received and responded to by the track relay TR, code detecting relay H picks up its contacts. Under this condition, the controlled wayside signal S displays the "approach" indication by virtue of lamp Y thereof receiving lighting current over a circuit which extends from the positive supply terminal through front contact 21 of relay H, back contact 22 of relay D180, conductor 27 and the lamp Y back to the negative supply terminal.

Finally, when the received trackway energy is of the 180 pulse per minute coding, both of the relays H and D180 pick up their contacts and the controlled wayside signal S then displays the 5 "clear" indication by virtue of lamp G thereof receiving lighting current over a circuit which may be traced from the positive supply terminal through front contact 21 of relay H, front contact 22 of relay D180, conductor 28 and the lamp 10 G back to the negative supply terminal.

Considering now the circuits through which the rails of the track section to the rear of each of the signal locations E, F etc. are supplied with coded energy, these include contacts 30, 31 and 32 15 of the three relays FP, BP and H. Depending upon the positional combination of these three contacts, the primary winding of the associated track transformer TT is periodically connected with the alternating current source B-C over 20 the one or the other of coding contacts 180 and 75 of device CT or it is steadily connected with the alternating current source for a protective purpose later to become evident.

In the event that a train occupies the track 25 section and thus continuously deenergizes the associated track relay TR at the entrance end thereof, the contacts of all three of the relays FP, BP and H are released and the rails of the track section to the rear then receive energy of the 30 75 pulse per minute coding over a circuit which may be traced from the supply terminal B through conductor 33, back contact 31 of relay BP, conductor 39, the coding contact 75 of device CT, conductor 35 and the primary of the track 35 transformer TT back to the supply terminal C.

When energy of this 75 coding is received and responded to by the track relay TR, all three of the relays FP, BP and H hold their contacts in the picked-up position. Under this condition, 40 the rails of the rear track section receive energy of the 180 pulse per minute coding over a circuit which may be traced from the supply terminal B through conductor 36, the coding contact 180 of device CT, conductor 37, front contact 45 tact 32 of relay H, conductor 38, front contact 31 of relay BP, conductor 40, front contact 30 of relay FP, conductors 41 and 35 and the primary of track transformer TT back to supply terminal C.

50 Likewise, when energy of this 180 coding is received and responded to by the track relay TR, the contacts of all three of the relays FP, BP and H are again picked up and the rails of the rear track section again receive energy of the 180 55 pulse per minute coding over the circuit which was traced in the preceding paragraph.

From the foregoing it will be seen that the organization of apparatus which is disclosed in Fig. 1 constitutes the trackway portions of a 60 three indication combined automatic block signalling and cab signalling system. In operation of this system, as long as all sections of the protected stretch of track 1-2 are vacant, the rails of each transmit energy of the 180 coding to the 65 code following track relay TR which acts upon the code detecting and distinguishing relays H and D180 in a manner causing the controlled wayside signal S to display the green or "clear" indication.

70 When, however, a train passes through the track stretch, the shunting action of its wheels and axles deenergizes continuously the track relay associated with each of the occupied sections. It, in turn, acts upon the associated decoding 75 relay apparatus in a manner causing it to pro-

duce the red or "stop" indication on the part of the controlled wayside signal S and to include coding contact 75 in the primary circuit of the track transformer TT which is connected to the rails of the track section to the rear of the signal 5 location.

Assuming that this rear section is vacant, the rails thereof transmit this 75 code energy to the track relay TR at the entrance end thereof and it, in turn, causes the associated relays to put 10 the controlled signal S at yellow or "approach" and to supply the track section to the rear of the location of that signal with energy of the 180 pulse per minute coding. Finally, in responding to this energy the track relay TR at the entrance 15 of the last named section causes the controlled wayside signal S to show the green or "clear" indication and the rails of the track section to its rear also to receive energy of the 180 coding.

It has already been pointed out that under a 20 certain positional combination of the contacts of relays FP, BP and H at each of the signal locations, the track circuit to the immediate rear thereof will receive steady or uncoded energy. In the organization of apparatus herein disclosed, 25 this particular combination of relay contact positions results only in the event of breakdown of the insulated joints 3 which electrically separate the rails of adjacent track sections. As will be explained more fully presently, it functions to prevent the controlled wayside signal S from giving a false "proceed" indication in response to the energy which flows from the rails of the track section to the rear over the faulty 30 insulated joint into the rails of the advance track 35 circuit and thence into the winding of the associated track relay TR.

The condition of joint failure discussed in the preceding paragraph is hazardous in that its usual effect is to cause the wayside signal S at 40 the location of the fault to give a "proceed" indication even though a train may occupy the track block which the signal guards. Assume, for example, that the joints 3 at location E break down upon the passage of a train through block E-F 45 of Fig. 1. This permits energy of the 75 coding to feed over the faulty joints from the rear section rails into the rails of the occupied forward section.

As soon as the rear of the train passes some 50 distance beyond the point of connection of the winding of track relay TR with the rails of this forward section, the potential between these rails resulting from the rear section leakage energy rises to a point sufficient to effect code following 55 operation on the part of relay TR. Acting in the normal manner through the associated decoding relays H and D180, this causes the controlled wayside signal Se to display the yellow or "approach" indication. Were the leakage energy allowed, as in the past, to remain coded, it would cause the energization of relay H. Relay H being energized would transfer the feed circuit for transformer TT from the 75 coding contact to the 60 180 coding contact and that, in turn, would cause the energization of relay D180. This would cause the display of a clear or green aspect by signal Se and thereby falsely advise the engineerman of a following train that the track section E-F is vacant when in reality it is occupied. 65

In the case of steam territory where the track rails 1 and 2 do not form part of a propulsion circuit through which driving energy is supplied to electric locomotives, the condition just stated results only in the event that both of the insu- 70 75

lated joints 3 at the signal location are defective simultaneously and thus interconnect rail 1 of the rear section with rail 1 of the forward section and rail 2 of the rear section with rail 2 of the forward section. In electrified territory, however, a single broken down insulated joint 3 is the full equivalent of the just described two broken down joints in steam road territory. This is because of the autotransformer action of the 10 impedance bonds 4.

Should, for example, the joint in rail 1 become defective and establish direct connection from the rear section length to the forward section length of that rail, there is completed by 15 the impedance bonds 4 a return path around the companion joint in rail 2 and this produces the same effect as were this second joint also to lose its insulating qualities. In electrified territory, therefore, the probability of the false proceed 20 signal indication previously discussed is comparatively high and requires special protection facilities to prevent accidents and damage in the event of a broken down rail joint.

In the improved form of organization of my 25 invention, this protection is effected at each signal location by the before mentioned circuits which normally feed coded energy to the track circuit to the rear and which are controlled by contacts 30, 31 and 32 of the forward section re-

lays FP, BP and H.

Referring to location E of Fig. 1, again assume that, while passing over the joints 3 at that location, a train causes either or both of them to break down and establish a path over which energy from the rails of the rear track section may feed into the rails of the forward section. Because of the presence of the train in the rear portion of the section E—F, relay TR is at first continuously deenergized and the contacts of all 35 three of the relays FP, BP and H are accordingly released. Under this condition, the rails of the section to the rear of location E are supplied with energy of the 75 coding over a circuit previously traced as including conductor 33, back contact 40 31 of relay BP, conductor 39 and the coding contact 75.

As soon as the rear of this train has passed far enough beyond the signal location to allow an "on" period of the 75 code energy (feeding 50 from the rear to the forward section over the defective joint and the impedance bond return path) to energize the track relay TR, front contact repeater relay FP becomes energized and picks up. Contact 30 now establishes what will 55 be termed a "lock-out circuit" over which steady energy is supplied to the rails of the rear track section. This lock-out circuit may be traced from power source terminal B through conductor 33, back contact 31 of relay BP, conductor 46, 60 front contact 30 of relay FP, conductors 41 and 35 and the primary of track transformer TT back to the supply terminal C.

In feeding over the defective joint to track relay TR, this steady energy holds it continuously 65 picked up. Relay FP, therefore, continues to remain energized while back contact repeater relay BP fails to receive any energy and thus retains its contact 31 in the released position in which the lock-out circuit is completed. At the same 70 time, released contact 18 of relay BP maintains relay H deenergized and its contact 21, in turn completes the lighting circuit for lamp R of the controlled wayside signal Se and thereby causes that signal to display the indication of "stop" 75

This "stop" indication by the signal at the

location of the defective joint continues uninterrupted as the train advances entirely out of the track block E—F and, in fact, until the broken down joint is repaired. This, of course, is because the steady energy which is supplied through the "lock-out" circuit feeds uninterruptedly over the defective joint into the winding of the track relay TR in advance and causes the contacts of relays FP, BP and H continuously to remain in the positions just described.

It has been seen that a "proceed" indication (either approach or clear) can be given by the controlled wayside signal S only when the code following track relay TR is in operation and it has been mentioned that code detecting relay H 15 is made somewhat slow in picking up. The reason for this delay is to ensure that should the track relay be momentarily deenergized from any cause while the lock-out circuit is in effect, such a proceed signal indication will not falsely be 20 given.

In the event of such momentary deenergization during lock-out conditions, relay BP receives current over back contact 10 of the track relay. In picking up, it interrupts at contact 31 the supply 25 of steady energy to the rear track circuit and continues this interruption until relay FP releases contact 11. At that time the contacts of relay BP are again released and the supply of energy to the winding of relay H is discontinued.

As already stated, the pick-up period for relay H is preferably made slightly longer (such as of the before stated order of six-tenths second) than the release period of the relay FP. This assures that the momentary deenergized condition of the 35 track relay TR above mentioned will be ineffective for causing relay H to pick up and change the indication of the controlled wayside signal S to either "approach" or "clear." Contacts 21 and 32 of relay H thus remaining continuously released, the signal is uninterruptedly held at "stop" and the 180 code supply circuit is kept 40 open at contact 32.

Following the sequence of operations just described as being occasioned by a momentary de- 45 energization of the track relay, the lock-out circuit automatically re-establishes itself upon the first "on" period of the 75 code, which again is supplied to the rear track section (from the terminal B connected to conductor 33 over back contact 50 31 of relay BP and coding contact 75 of device CT) as soon as repeater relays FP and BP both become released. In feeding over the defective joint to the winding of the track relay, this "on" 55 pulse picks up the contacts of that relay and energizes relay FP. Contact 30 thereof once more completes the lock-out circuit and thus assures that the controlled wayside signal S will continuously be held at "stop."

In the above operations incident to automatic 60 restoration of the lock-out circuit following a momentary deenergization of the track relay, it will be seen that reliance is placed upon the opening by contact 11 of relay FP of the snubbing circuit for relay BP, thereby permitting the contacts 65 of the latter relay to drop out almost immediately upon the opening of the contacts of relay FP. This quickens the cut off of energy to the winding of relay H and thus allows the minimum pick-up delay of that relay to be considerably 70 shorter than would be permissible otherwise.

The just described lock-out circuit also becomes effective in the event that an insulated rail joint should break down when the protected track sections are vacant. Under these conditions all 75

of the track circuits are receiving energy of the 180 coding prior to the joint failure and the wayside signal at the entrance of each block is displaying the green indication of "clear."

5 If, now, an insulated joint breaks down to practically zero resistance, the track relay at the faulty location receives such a large amount of energy from the code being supplied to the track circuit to the rear (when this rear code is in step 10 with the forward code) that its contacts will occupy the picked-up position for a much longer percentage of the total time than they occupy the released position. This characteristic is inherent in the single element track relay design 15 and results from the fact that abnormally high values of relay energizing current pick up the contacts more quickly and introduce a corresponding delay to their release because of the higher intensity of magnetic flux. This flux 20 must, of course, die down to a predetermined value before the contact carrying armature can be released under the biasing action of the usual spring or of gravity.

In consequence of the lengthened picked-up 25 periods of the track relay contacts and of the shortened released periods thereof which the assumed conditions produce, the intermittent energization of the back contact repeater relay BP is reduced to the point that that relay releases 30 its contacts regardless of the relative positions of the energy pulses of the forward and rear section codes which combine to energize relay TR. In the meantime, of course, the front contact repeater relay FP remains picked up and in this 35 manner "lock-out" is produced upon the release of relay BP.

If, while the track relay is responding to 180 code, and 180 code is being supplied to the track circuit to the rear, an insulated joint breaks 40 down to have an appreciable value of resistance, say of the order of five-tenths ohm, the track relay TR will continue to respond to the two 180 codes as long as these two codes remain approximately in phase or have a relation in which their 45 "on" and their "off" periods occur approximately in step. Under this condition the operation of the track relay is not sufficiently altered from normal to cause back contact repeater relay BP to drop out in the manner already described and 50 the controlled wayside signal thus continues to display "clear."

Since, however, the two coding devices CT which supply the rails of the forward and the rear track sections, respectively, are usually driven by 55 separate induction motors the relative speeds of which cannot help but vary somewhat, the in-phase relation of the codes will not be a continuous one and gradually they will fall out of step. As they approach the condition in which the 60 "off" period of one code is filled in by the "on" period of the other code, the track relay TR will again remain picked up continuously, thereby releasing relay BP and producing "lock-out" in which the controlled wayside signal displays the 65 red or "stop" indication.

Assume next that the insulated joint breaks down at a time when dissimilar codes are present in the track rails on the two sides of the joint, as for example, 75 code in the forward section 70 and 180 code in the rear section. If the joint breaks down to practically zero resistance, track relay TR will again receive such a large amount of energy from the code being applied to the track circuit in the rear (when the pulses of that rear 75 code fall into meshing relation with those of the

forward code) that the relay will maintain its contacts picked up for a much greater percentage of the time than they are released. As in the case of the similar codes previously described, this will cause the back contact repeater relay BP to 5 release to produce "lock-out" and cause the controlled wayside signal S to show "stop."

If, under the conditions stated at the beginning of the preceding paragraph, the insulated joint breaks down to have a substantial resistance of 10 the previously assumed order of five-tenths ohm, track relay TR will attempt to respond to both of the two codes. This, of course, will cause the contacts of the relay to be picked up a much larger percentage of the time than they are released. Again, this will result in the release of the back contact repeater relay BP to produce "lock-out" and a display of "stop" by the wayside signal. 15

In those unusual instances in which a defective 20 insulated joint may fail to produce "lock-out", this action is delayed only until a train passes over the affected track circuits in the normal direction of traffic. The first train to do this produces "lock-out" in the manner previously explained 25 and thus protects following train movements. In this connection it is to be observed that a following train in the normal direction of traffic will, of course, "unlock" the circuit during the particular period that the train is passing over the defective joint. However, when the rear of 30 this train is several rail lengths past the faulty joint, the circuit will again "lock-out" due to the feeding of energy from the rear track circuit over the joint and to the winding of the track relay TR. 35

The protection facilities herein disclosed are 40 especially adapted for use with systems of automatic block signalling wherein single element track relays of the type shown at TR are employed. For many installations this single element type of relay is preferred in place of the conventional two element track relays for the reason that its use requires no line conductors between adjacent signal locations for local energy supply. Moreover, the fact that it gives a non-polarized form of response provides further 45 advantages later to be discussed.

One very practical feature of the lock-out circuit just described is that it is not dependent upon relative polarity of the track circuits on the opposite sides of the joint. In addition to protecting against the usual failure of the joint which has already been described, the circuit is thus also capable of protecting against a further type of failure wherein one rail of one of the track circuits may become connected to the opposite rail 55 of the adjacent track circuit.

This second type of failure sometimes does occur and may be caused, for example, by a connection between the track relays and the track junction box or may result when the conductors are 60 accidentally pinched under the box lid or when the insulation comes off the conductors and allows them to come into direct contact with the metallic portions of the box. If the protection depended upon the use of the usual two element 65 track relay and the staggering of track circuit polarities, the condition just described would result in a false clear signal instead of the desired "stop" indication produced by the lock-out circuits of Fig. 1. 70

The particular form of lock-out circuit represented at location E in Fig. 1 provides for a check in the operativeness of the facilities through which steady energy from power source terminal B is supplied by way of conductor 33 over the 75

back contact 31 of relay BP. Should this connection accidentally become broken, the track circuit to the rear of location E could under no circumstances receive energy of the 75 coding and in the event of failure of one of the joints 3 at the named location at a time when a train was in the forward portion of track section E-F, the track relay TR would continue to remain deenergized and hold the controlled signal S at stop. Moreover, should the connection involving conductor 33 break simultaneously with the breakdown of one of the insulated joints at location E there again would be no energy available with which to pick up the track relay contacts and the desired "stop" aspect of the signal would still result.

Comparable checking of the operative condition of the connections which involve conductor 40 of the lock-out circuit may be provided by modifying the just described fundamental form of this circuit in the manner shown at location F in Fig. 1. Here, conductor 39 from the front point of the coding contact 75 is connected to the back point of contact 30 of relay FP instead of being joined directly with conductor 40 as shown in Fig. 1 at location E.

From an inspection of the connections shown at location E, it will be seen that were the connection 40 to be broken, the desired form of operation of the lock-out circuit would be interfered with. That is, energy then still could feed over back contact 31, conductor 39, the 75 coding contact, conductor 35 and the track transformer TT to the rails of the rear track section and thus produce false "proceed" signal indications against which the now disabled lockout circuit would be incapable of guarding. Still further energy might be fed over the 180 coding contact through front contact 32 of relay H, conductor 38, front contact 31 of relay BP, conductor 39, the coding contact 75 and thence to the track transformer TT. This would result in a distorted 180 code being received by the rear track circuit which, under certain conditions, will produce a "proceed" indication on the part of the wayside signal or a train carried cab signal which may be under the control of this distorted code.

When, however, the connections are modified in the manner shown at location F, the undesirable conditions just named are eliminated and conductor 40 becomes completely checked because a break in this conductor will positively open the circuit through which both the 75 code and the 180 code must feed to the track transformer. In the modified arrangement of location F, for example, the 75 code feed must be carried over back contact 31 of relay BP, conductor 40, back contact 30 of relay FP and conductor 39.

From examination of the modified lock-out circuit that is disclosed at location F in Fig. 1, it will be seen that the normal operation thereof in selecting the coding of the energy supplied to the rear track circuit and also its operation in effecting a lock-out in the case of a broken down insulated joint is the same as in the basic form of circuit previously described in connection with the disclosure thereof at location E of Fig. 1. It thus differs therefrom only in providing a further safeguard against failure or improper operation.

The effect of the steady lock-out energy on succeeding track circuits to the rear is to cause all wayside signals S associated therewith to be put at "stop" back as far as the next interlocking or properly arranged cut section. This

effect is produced by what will be termed a "cascade action" of the steady energy.

In this action where no cut section is used, the rails of the section immediately behind the broken down insulated joint transmit the steady energy to the track relay TR at the entrance thereof. In holding its contacts continuously picked up, this relay continuously energizes the front contact repeater relay FP associated therewith and deenergizes the back contact repeater relay BP. These relays, in turn, set up the lock-out circuit for the next track section to the rear. At the entrance thereof the action just described is repeated and so on as far back as the track circuits are continuous.

In installations where the distance between interlockings is more than several blocks, it ordinarily is desirable to break up this cascade action of the steady energy. Such a breaking up can very readily be effected where cut section facilities of the character represented at location Ea in Fig. 1 are used. As there represented, these facilities consist of the single element code following track relay TR connected to receive energy from the forward portion of the divided signal block, a repeater relay BP controlled over the back contact 40 of relay TR, the usual track transformer TT connected to the rails which constitute the rear portion of the divided signal block through current limiting reactor 6, and contacts 43 and 44 respectively carried by the relays TR and BP and arranged to control a connection of the primary winding of the track transformer with the alternating current power source B-C.

In operation of the facilities shown at cut section location Ea, relay TR follows the coding of the energy which it receives from forward location F and thus causes slow release relay BP to hold its contact 44 continuously picked up as long as this code following operation takes place. This sets up the circuit over which contact 43 of relay TR periodically makes and breaks the primary current supply circuit for transformer TT. Each time, now, that relay TR picks up in response to a pulse of forward circuit energy, the rails to the rear of location Ea receive a pulse of energy from transformer TT. Likewise, each time that relay TR releases its contacts, this supply of energy to the rear circuit is discontinued. In this manner the trackway code is repeated around the insulated joints 3 which define the cut in the signal block.

In case, however, that the apparatus at location F supplies steady lock-out energy to the rails of the track section Ea-F, relay TR at cut location Ea remains continuously picked up, contact 44 of relay BP is released and the rails of track section E-Ea are then continuously deenergized. In this manner, the before described cascading action of the steady energy is broken up. The track section to the rear of location Ea now has a continuously deenergized condition and the associated wayside signal S shows "stop" in the same manner as were the track section to be occupied and the rails thereof by-passed by the train wheels and axles.

In addition to repeating the trackway code and breaking up the cascade action of the steady energy, the facilities at cut section Ea also automatically protect against a broken down insulated joint 3 at that location. If this breakdown is present when the forward section Ea-F is occupied, the relay TR connected to the rails

thereof will, of course, receive no energy and the supply circuit for the rear section E—Ea will continuously be interrupted. As the train proceeds into the next block or beyond location 5 F and 75 code energy is supplied to section Ea—F, the first "on" period of this code picks up relay TR and until the contacts of repeater relay BP drop out energy is supplied to the rails of the rear track section over the 10 previously referred to circuit which extends from the supply terminal B through front contact 44 of relay BP, front contact 43 of relay TR, conductor 45 and the primary of transformer TT back to supply terminal C.

15 In feeding back over the defective joint 3 at location Ea this energy holds the track relay at that location continuously picked up until the release period of repeater relay BP has expired. At that time the supply of energy to the rear 20 circuit is again interrupted and upon the reception by relay TR of another pulse of coded energy from location F the sequence of operations just described is repeated. This results in a mutilation of the code which is repeated around the defective rail joint which 25 is of such a nature as to cause excessively long "on" periods of the energy impressed upon the rails of the rear track circuit.

Because of the before explained characteristics of the decoding equipment at the signal location E in the rear, this type of mutilated code is ineffective for producing a higher proceed indication on the part of the controlled wayside signal Se. And because the frequency of the 30 code which is repeated around the faulty joint at the cut section location is decreased rather than increased, the type of cut section facilities represented at location Ea provides safety for all applications in which the lowest frequency code is identified with the lowest or most restrictive "proceed" indication.

For applications wherein it is permissible that steady energy be repeated around the cut section joint into the rear track circuit, the simplified facilities shown in Fig. 2 may be employed. In 45 these, the rear section energy is directly coded over the front contact 43 of the code following relay TR which is identified with the forward section. Not only is each "on" and "off" period of coded energy in the forward track circuit repeated into the rails of the rear track section but steady energy in the forward section likewise produces steady energy in the rear section.

As regards protection against a broken down 55 insulated joint at this cut section, the facilities of Fig. 2 have slightly different characteristics than those shown at Ea in Fig. 1. While the forward track section is occupied by a train, relay TR is, of course, deenergized and in the 60 event of a broken down joint the absence of supplied energy in the rear section prevents the track relay TR from being energized over the broken down joint. When, however, the train passes beyond the exit end of the forward 65 section, the first impulse of coded energy transmitted over the forward section rails picks up relay TR, completes the energizing circuit for transformer TT and thus effects the continuous energization of relay TR over a circuit which 70 includes the defective joint. This establishes a lock-out circuit similar in characteristics to the lock-out circuit at each of the signal locations E and F of Fig. 1.

75 Referring to Fig. 3, I have there shown a

third form of cut section facilities which incorporate the improvements of my invention. As in the case of the apparatus shown at location Ea in Fig. 1, these facilities are suitable for use when it is desirable to break up the 5 cascade action of the steady lock-out energy. In addition, the Fig. 3 cut section may be used where the location thereof marks the beginning of an approach locking section of track which is identified with a track switch (not shown). 10

Here, both a front contact repeater relay FP and a back contact repeater relay BP are used in conjunction with the code following track relay TR, and the approach locking contact 47 is arranged to be operated by relay BP. Control 15 of the energizing circuit for transformer TT which is connected to the rails of the rear track section is effected by means of contacts 43 and 44 of relays TR and BP in the same manner as at location Ea in Fig. 1. Relay FP, controlled 20 in the same manner as at locations E and F of Fig. 1, is additionally employed to insure that the approach locking contact 47 will be picked up only when the track circuit beginning 25 at location Fa receives coded energy.

As regards protection against broken down joints at the cut section location Fa, the facilities of Fig. 3 have the same characteristics as those shown at Ea in Fig. 1. Also, in case of steady 30 energy being received from the forward track circuit, Fig. 3 has the same characteristics as Ea of Fig. 1; namely, that no energy will be fed to the track circuit to the rear of the cut section rail joints 3.

From the foregoing analysis of the lock-out 35 circuits which are disclosed in Fig. 1, it will be seen that the three relays FP, BP and H which are controlled by the code following track relay TR at each of the wayside signal locations pick up in a definite sequential manner each time that coded energy is first received from the rails of the associated track section following the vacation thereof by the rear end of a train which is passing therethrough. That is, upon the first "on" period of this initially received code, relay 45 FP is picked up over front contact 10 and conductor 12; during the "off" code period which follows, relay BP is picked up over back contact 10 of relay TR and front contact 11 of relay FP; and some time later, which is slightly longer 50 than the duration of the second "on" period of the received trackway code, slow responding relay H picks up as a result of having previously received energizing current over front contact 18 of relay BP. Speaking with reference to the 55 contacts of relay H, there is thus provided what will be termed a "three point pick-up," this term referring to the fact that three periods of trackway code must be responded to by relay TR before the contacts of relay H can be picked up following each resumption of coded energy supply to the track circuit.

In controlling the lock-out circuits already described, this "three point pick-up" performs an important function. The first action thereof sets 65 up the steady energy lock-out circuit at contact 30, which is completed over back contact 31 of relay BP. If an insulated joint is broken down, the relay pick-up cycle advances no further as the steady energy now feeds from the rear track 70 circuit over the defective joint and holds the track relay TR continuously energized and the controlled wayside signal S continues to show "stop."

If, however, the rail joints 3 are effective for 75

performing their intended insulating functions, the second step of the three point pick-up takes place and the supply of steady or lock-out energy to the rear track circuit is broken at contact 31 of relay BP. During this second stage, the rear section rails receive no energy at all. This is followed by the third stage which corresponds to the second "on" period of the resumed trackway code and during which relay H picks up. Contact 32 thereof now completes the 180 coding circuit for the rear section track transformer. This circuit continues active as long as the track relay TR continues to effect a normal response to coded trackway energy.

It will thus be seen that (with the advance section of track occupied) the disclosed lock-out circuit provides inherent protection against the giving of a false "proceed" signal indication as long as the lock-out circuit remains active regardless of whether that steady energy circuit may be intermittently opened and closed. Such an intermittent condition may, of course, be in the wiring, track transformer TT, reactor 6, rail connections, the defective insulated joints 3, or the track relay TR. In the event of such an opening, the track relay releases; that release breaks (at contact 10) the energizing circuit for relay FP and picks up (over contacts 10 and 11) the companion relay BP; and that pick-up of relay BP removes (at contact 31) the steady energy connection from the lock-out circuit and completes (at contact 18) the energizing circuit for relay H. Before, however, relay H has time to pick up, relay FP releases (due to the fact that the period of release delay for relay FP is chosen to be shorter than the period of pick-up delay for relay H) and interrupts (at contact 11) both the energizing and the snubbing circuits for relay BP. Relay BP now immediately drops out and deenergizes (at contact 18) relay H still before the latter has had time to pick up. Hence contact 21 of relay H continues to hold the controlled wayside signal S at "stop" even though the lock-out circuit is opened in the manner just described. After such momentary opening, moreover, reclosure of the lockout circuit still does not discontinue the "stop" indication on the part of the controlled signal. Following such reclosure, the first pick-up of the track relay TR (by rear section energy leaking over the faulty rail joint in the manner already explained) picks up relay FP, restores the supply of lockout circuit energy to the rear section rails (and to the track relay TR), and by causing relays BP and H to stay released holds the controlled signal at "stop." Under the stated conditions of intermittent opening and closing of the lockout circuit, therefore, no false "proceed" indication is produced. Still further, it is not possible under those conditions for the track relay and the BP relay to be picked up simultaneously because once released the track relay cannot again be picked up (with the advance track section occupied) unless relay BP is released (to set up a rear section energy supply connection over back contact 31) and once picked up and there continuously held the track relay TR prevents (at contact 10) the energizing circuit for relay BP from being completed.

Referring now to Fig. 4, I have there disclosed a second arrangement of circuits for effecting the just described "three point pickup" action on the part of relays FP, BP and H. The circuits over which contact 10 of the code following relay TR supplies energizing current to the windings of relays FP and BP are the full equivalent of

those shown in Fig. 1. The code detecting relay H1, however, differs from the corresponding relay H of the earlier figures both in its response characteristics and in the circuits over which it receives energizing current.

Whereas the relay H of Fig. 1 is preferably of the ordinary ferrule type providing delayed action both in the pick-up and the release operation of the contact, the relay H1 of Fig. 4 is of a normal responding type which is rendered slow releasing by the use of a snubbing resistor 48 which is bridged across the relay winding in the usual manner. Also, instead of having but a single energizing circuit, relay H1 is provided with: (1) a "pick-up" circuit which includes front contact 10 of relay TR, a conductor 49, a back contact 50 of the relay itself and front contact 18 of relay BP; and (2) a separate "stick" circuit which includes front contacts 50 and 18 of devices H1 and BP.

An inspection of the circuit arrangement of Fig. 4 will show the operation described below when coded energy is applied to the track circuit to which the code following track relay TR is connected. The first "on" period of the code picks up relay TR and thereby energizes relay FP. The succeeding "off" period of the code releases relay TR and energizes repeater relay BP over the back contact 10 of device TR and front contact 11 of device FP. The second "on" period of the received code picks up relay TR and supplies energizing current to the winding of relay H1 over the before referred to pick-up circuit which extends from the positive supply terminal over front contact 10 of relay TR, conductors 12 and 49, back contact 50 of relay H1, conductor 52, front contact 18 of relay BP, conductor 19 and the winding of relay H1 back to the negative supply terminal.

As the relay H1 picks up and opens its back contact, the pick-up circuit just traced is broken but the relay has been heavily energized thereover and hence has no difficulty in continuing the pick-up action to the point where its front contacts close. This completes the before referred to stick circuit through which holding current is supplied to the winding of relay H1 over a path from a second positive terminal of the before referred to supply source through front contact 50 of relay H1, conductor 52, front contact 18 of relay BP, conductor 19 and the winding of relay H1 back to the negative supply terminal. Under the action of this stick circuit, relay H1 holds its contacts picked up until the circuit is broken by a release of contact 18 of relay BP.

As shown in Fig. 4, relays FP, BP and H1 may be included in the signal location equipment of a three indication automatic block signalling system in the same manner as are relays FP, BP and H of Fig. 1. Thus, code following track relay TR of Fig. 4 is connected through the before described resonant rectifying unit 7 to receive operating energy from the rails 1 and 2 of a track section of which location K marks the entrance. In addition to contact 10, which controls the remaining three relays under discussion, it is provided with a contact 8 which pole changes the decoding transformer DT to produce in the secondary thereof a code frequency alternating current voltage which feeds through a selective unit J180 to the winding of a code distinguishing relay 180. This relay is arranged to pick up only when relay TR responds to trackway energy of the 180 coding. Code detecting relay H1, however, picks up in the event that energy of either the 180 or the

75 coding is received. Through contacts 21 and 22 relays H1 and D180 control the wayside signal Sk in the usual manner.

Contacts 30, 31 and 32 of relays FP, BP and H1 are included in circuits through which the alternating current source B-C is connected with the primary winding of the rear section track transformer TT either through one of the coding contacts 15 or 180 of transmitter CT or directly to supply steady energy thereto. This rail supply circuit includes the "lock-out" features already described and in all other respects is identical with the correspondingly identified circuit facilities shown at location E in Fig. 1.

From an inspection of the circuits of Fig. 4 and a consideration of the foregoing description thereof, it will be apparent that from an operating point of view these are generally equivalent of the organization of circuits which is shown at location E in Fig. 1. The major distinguishing feature is the employment by code detecting relay H1 of what will be referred to as a "back contact" pick-up circuit, this term having reference to the fact that pick-up energy for the relay is transmitted over back contact 50 thereof.

As has been seen, this energy is interrupted when the relay armature has advanced through a range of travel wherein the back contact opens. Due, however, to the momentum of the moving armature and also to a selection of circuit constants which causes the flow of pick-up current through the relay winding to be especially heavy, the pick-up movement readily continues from the point of back contact opening to the point of front contact closing and thus the relay H1 operates in the manner intended. Proper performance in this respect may be assured by providing more than the usual flexibility in the contact spring (not shown) upon which is mounted the back point with which contact 50 engages in the released position. Further benefits along the same line may be provided by making a corresponding adjustment in the spring (also not shown) carrying the front point which contact 50 engages in the picked-up position to complete the stick circuit for the relay.

One advantage of this back contact pick-up arrangement is that it permits the retardation characteristics of the relay to be determined solely by the electrical constants of its own energizing circuit and to be independent of the electrical constants of the common energizing circuit for relays FP and H1 of which common circuit front contact 10 of relay TR forms a part. By disconnecting the winding of relay H1 from this common circuit when the relay contacts are picked up, its holding circuit is entirely independent of that common circuit and its retardation is therefore determined solely by the electrical constants of its own energizing winding.

From a further inspection of Fig. 4, it will be seen that in the event of a broken down insulated joint at location K with a train occupying the forward portion of the track section of which that location marks the entrance, relay H1 can never be picked up to produce a false "proceed" indication on the part of the wayside signal Sk for the reason that it picks up only on the second "on" interval of code pulse energization of the track relay TR and this cannot occur with the circuit as shown in Fig. 4 when the source of the coded energy which feeds forwardly over the defective joint to the track relay is at the location where the defect exists. Moreover, since the H1 relay requires that the track relay TR and the

repeater relay BP be picked up simultaneously before it can pick up its contacts, it is evident (from the earlier given analysis of how relays TR and BP are coordinated) that an intermittent opening and closing of the "lock-out" circuit of an occupied block will be ineffective for picking up the H1 relay contact. This is an essential requirement of any lock-out circuit which is built around the single element code following track relay TR when applied to double rail electric road track circuits in the manner disclosed in each of the drawing figures.

Another feature which is peculiar to the circuit organization of Fig. 4 is the use of a second resistor unit 54 in the snubbing circuit of the back contact repeater relay BP. The purpose of this resistor 54 is to decrease the period of contact release for relay BP when the track relay TR is responding to trackway energy of the 180 pulse per minute coding. In that event, a shunting circuit for the added resistor is maintained open by a picked-up contact 55 of the code distinguishing relay D180. It will be noted that resistors 54 and 16 are serially connected with front contact 11 of relay FP in the referred to snubbing circuit. When both of these resistors are effective, relay BP is arranged to have a release period just slightly greater than the "off" intervals of the mentioned 180 trackway code.

In the event that the low speed or 75 pulse per minute code is received and responded to by the relay TR, code distinguishing relay D180 releases and closes at contact 55 the mentioned by-passing circuit for resistor 54. Under this condition, resistor 16 only is effective in the snubbing circuit and, in consequence, the release time of relay BP is increased to a value somewhat greater than the longer spacing or "off" periods of the 75 code.

While not essential in all applications, the just described use of the added snubbing resistor 54 is a further refinement which has been found somewhat to improve the operating characteristics of the circuits in applications where conditions are especially critical. In other words, by splitting the snubbing resistor for relay BP into two portions, as represented in Fig. 4, it is possible more fully to guarantee that the lock-out circuit which this relay aids in controlling will operate positively under all conditions.

In situations where the peculiar advantages and operating features of the just described "back contact pick-up" for the code detecting relay are not required or desired, use may be made of one or another of the three alternative forms of energizing circuits which are disclosed in Figs. 5, 6 and 7. In all three of these figures the three relays FP, BP and H1 are shown as being applied to a three indication signaling system which is comparable to that previously described in detail in connection with Figs. 1 and 4.

Thus, in Fig. 5 the equipment is associated with a code following track relay TR which receives operating energy from the rails of the track section of which location M forms the entrance; in Fig. 6, the track relay TR is also shown as being of the direct current type receiving through resonant transformer unit 7 operating energy from the rails of a track section of which wayside signal location O marks the entrance; and in Fig. 7, the three relays under consideration are associated with an alternating current track relay TR of the single element code following type which receives energy from the rails of a track section of which signal location Q marks the entrance.

Referring first to Fig. 5, the equivalent of the

back contact pick-up circuit for relay H_1 is provided through the use of a pick-up circuit which includes front contact 8 of the track relay TR, conductor 23, a rectifier 57, conductors 60 and 52, front contact 18 of relay BP, conductor 19 and the winding of relay H_1 . In effect this pick-up circuit is connected in multiple with the circuit over which the upper portion of the primary of the decoding transformer DT is supplied with energizing current. The rectifier 57 is included for the purpose of preventing the energy which a "stick" circuit for the relay H_1 transmits from interfering with the operation of the decoding transformer and also to prevent reverse inductive kicks from the transformer from tending to deenergize the relay.

This stick circuit is a duplicate of that shown in Fig. 4 with the exception that a resistor 58 is included therein for the purpose of cutting down the current from the relatively high value necessary in the arrangement of Fig. 4 to a lower value which is adequate for operating the relay by means of the arrangement of Fig. 5.

As in the case of Fig. 4, the "three point pick-up" action is produced by the circuits of Fig. 5. That is, the first "on" period of coded energy initially received by relay TR picks up contact repeater relay FP; the following "off" period of the code causes back front contact repeater relay BP also to be energized and picked up; and the second "on" period of the received code completes the pick-up circuit for relay H_1 which has now been set up by front contact 18 of relay BP. This circuit may be traced from the positive supply terminal through front contact 8 of relay TR, conductor 23, rectifier 57, conductors 60 and 52, front contact 18 of relay BP, conductor 19 and the winding of relay H_1 back to the negative supply terminal.

In picking up, contact 50 of relay H_1 now completes the stick circuit through which the winding receives current which holds it continuously picked up until such time as contact 18 of relay BP may be released. This stick circuit may be traced from the positive supply terminal through resistor 58, front contact 50 of relay H_1 , conductor 52, front contact 18 of relay BP, conductor 19, and the winding of relay H_1 back to the negative supply terminal. As has been pointed out, rectifier 57 prevents a reversal of current from the stick circuit into the primary winding of the decoding transformer DT.

Referring next to Fig. 6, the arrangement there disclosed makes use of a fourth relay HP which is a front contact repeater for relay H_1 . It is an ordinary acting relay and carries the contacts 21 and 32 which are included respectively in the signal control and code selecting circuits of the associated signal location equipment and which perform the same functions as the correspondingly numbered contacts of relay H_1 in the systems of Figs. 4 and 5.

The winding of this fourth relay HP receives energizing current over a front contact 61 of relay H_1 . Relay H_1 , in turn, is provided with a pick-up circuit which includes front contact 10 of relay TR, conductor 49, a back contact 62 of relay HP, conductor 63, front contact 18 of relay BP, conductor 19 and the winding of the relay. It is also provided with a stick circuit which includes a resistor 58, front contact 62 of relay HP, front contact 18 of relay BP and conductor 19.

Like Fig. 5, the arrangement of Fig. 6 retains the "three point pick-up" characteristics. That is, the first "on" period of coded trackway en-

ergy which is initially received by track relay TR picks up repeater relay FP over front contact 10; the following "off" period of the code picks up repeater relay BP over back contact 10 and front contact 11 of relay FP; and the second "on" period of the received trackway code picks up relays H_1 and HP in rapid succession.

The pick-up circuit for relay H_1 may be traced from the positive supply terminal through front contact 10 of relay TR, conductors 12 and 49, 10 back contact 62 of relay HP, conductor 63, front contact 18 of relay BP, conductor 19 and the winding of relay H_1 back to the negative supply terminal. In picking up, contact 61 of relay H_1 picks up repeater relay HP over a circuit which 15 extends from the positive supply terminal through front contact 61, conductor 64 and the winding of relay HP back to the negative supply terminal.

In picking up, contact 62 of relay HP interrupts the pick-up circuit for relay H_1 and completes for that relay a stick circuit which extends from the positive supply terminal through resistor 58, front contact 62 of relay HP, conductor 63, front contact 18 of relay BP, conductor 19 and 25 the winding of relay H_1 back to the negative supply terminal. By virtue of the delayed release characteristics imparted by the snubbing resistor 48, relay H_1 readily bridges the short interval of time that contact 62 of relay HP requires to shift 30 from the released to the picked-up position.

Referring next to Fig. 7, I have there represented a third scheme for eliminating the "back contact pick-up" on the part of relay H_1 . In this scheme, a third or additional contact 66 is 35 provided on the track relay TR and it, together with contact 18 of relay BP, is included in the pick-up circuit for relay H_1 . In addition to this pick-up circuit, relay H_1 is provided with a stick circuit which is a duplicate of that shown in 40 Fig. 5.

Like the arrangements of Figs. 5 and 6, the circuit organization of Fig. 7 retains the "three point pick-up" characteristics. That is, the first "on" pulse of coded trackway energy initially received by relay TR picks up repeater relay FP; the following "off" period of the code picks up repeater relay BP; and the second "on" period of the received code picks up relay H_1 over a circuit extending from the positive supply terminal through front contact 66 of relay TR, conductors 67 and 52, front contact 18 of relay BP, conductor 19 and the winding of relay H_1 back to the negative supply terminal. In picking up, contact 50 of relay H_1 completes the stick circuit for that relay which may be traced from the positive supply terminal through resistor 58, front contact 50 of the relay, conductor 52, front contact 18 of relay BP, conductor 19 and the winding of the relay back to the negative supply terminal.

It has already been pointed out that under certain conditions steady or uncoded energy may be supplied to the rails of certain of the track sections of each of the coded signalling systems described herein. These conditions are not restricted to the "lock-out" functioning of the rail supply circuits in the event of broken down rail joints but they also include detection functions of one form or another. One example of the latter 70 may involve the control of highway crossing signals which are associated with a cut section location intermediate the ends of a signal block length of the protected track stretch.

For applications to track sections which are 75

supplied at times with such steady "detection" energy, prior art coded systems of all types known heretofore are subject to the disadvantage of producing a momentary false "approach" indication on the part of the controlled signal S in the event that a following train enters the track section and shunts the track relay during the time that the steady or uncoded energy is being received. This is for the reason that immediately preceding such a shunting, the contacts both of the track relay TR and of the repeater relay FP are picked up under the control of the steady energy then being supplied to the trackway.

When, now, the mentioned shunting does occur, the resulting release of the track relay completes, at contact 10, the energizing circuit for the second repeater relay BP and thereby picks up this relay. When, as in the referred to prior art systems, this relay BP directly picks up the code detecting relay H without delaying its response, the controlled wayside signal is thereby caused to interrupt the "stop" indication (which should be displayed continuously) and to give a false "approach" indication for a period equal to the release time of the repeater relays FP and BP.

In the improved arrangement disclosed in each of Figs. 4, 5, 6 and 7 (and in Fig. 1 also), this false approach indication is prevented since, under the conditions stated, only two of the three steps required for the energization (or pick-up) of the signal controlling relay H₁ (HP in Fig. 6 and H in Fig. 1) have been performed. The necessary cycle and one-half of received code not being simulated, the H relay maintains its contacts continuously released and in consequence the "stop" signal indication is not interrupted.

The benefits just stated for the systems of Figs. 4, 5, 6 and 7 are also realized from the embodiment of my invention which is disclosed in Fig. 1. Although there the code detecting relay H is solely controlled by the second repeater relay BP, that relay H is a slow responding device. Since in the system of Fig. 1 the period of pick-up delay of relay H is longer than the release delay of the repeater relays FP and BP, the three point pick-up characteristics of the arrangements of Figs. 4, 5, 6 and 7 are simulated and the desired interruption of the "stop" signal indication is prevented.

Referring next to Fig. 8, I have there represented a modification of the cut section facilities shown at location Ea in Fig. 1. In this modification of Fig. 8, a front contact repeater relay FP is substituted for the back contact repeater relay BP of Fig. 1, and coding of the energy supplied to the rails of the rear track section is effected over the back instead of the front point of contact 43 of the code following track relay TR which is operated by energy received from ahead. This arrangement also breaks up the cascade action of the steady energy which at times, as in the case of lock-out circuit operation, is impressed upon the forward section rails.

In case such steady energy is received from ahead, contact 43 of relay TR is continuously picked up and the track section to the rear accordingly receives no energy at all. When coded energy is received from ahead, it will be apparent that each "off" period thereof produces an "on" period of the code repeated in the rear track section by virtue of contact 43 completing the rail energizing circuit when in its released position. Likewise, each "on" period of the received code

produces an "off" period of the code which is repeated in the rear track section.

As regards protection against broken down rail joints at location Ea, the facilities of Fig. 8 have slightly different characteristics than those shown at the corresponding cut section in Fig. 1. In the event of such a faulty joint, the track relay TR still responds to each "on" period of coded energy received from ahead and by periodically energizing relay FP over contact 10, it causes that relay to maintain its contact 44 continuously picked up. However, during each "off" period of the code received from the forward track circuit, what is termed a "door bell" code will be fed to the rear track circuit when a broken down joint is present at the cut section location.

This door bell code is always of a considerably higher frequency than the normal 75 and 180 codes used in the train control systems. Ordinarily it will vary within the range of from 300 to 600 cycles per minute and from a test of commercial apparatus arranged as shown in Fig. 8 the frequency of the door bell code was found usually to be within a few percent of 500 cycles per minute or approximately 8 cycles per second. The following actions are involved in its production.

As back contact 43 of relay TR releases and completes the rail supply circuit for the rear track section, the resulting energy transmitted thereto feeds over the defective rail joint 3 at the cut section location Ea and is transmitted by circuit 7 to the winding of track relay TR. In responding, this relay frequently does not pick up completely but rather raises its contacts only to the point where contact 43 breaks the rail supply circuit. Once this happens, the supply of joint leakage energy is cut off from relay TR and contact 43 again completes the rail supply circuit. The cycle of operation just described is rapidly repeated and as a result the high frequency "door bell" code is produced continuously during each "off" period of the coded energy which is received from the forward track circuit.

Inasmuch as the decoding equipment of both the wayside and locomotive signal control facilities is incapable of responding to the individual pulses of this high frequency door bell code, it ordinarily will have the same effect thereon as a continuous pulse of track circuit energy. In consequence, the equipment to the rear of the cut section location Ea of Fig. 8 will continue to receive a code of the same fundamental frequency (75 or 180 cycles per minute) as that which is effective in the track circuit ahead of the cut section location. The rear section code differs, however, in that each "off" period thereof corresponds to an "on" period of the forward section code and further in that each "on" period of the rear section code is made up of "door bell" pulses instead of the simple 100 cycle alternating current waves from source B-C.

In situations in which the decoding equipment which is influenced by this rear section energy responds to the "on" periods in the same manner as were they of the usual 100 cycle wave, the cut section facilities of Fig. 8 are as effective as those shown at location Ea in Fig. 1. In certain applications, however, it has been found that the just described "door bell" code may produce a false "approach" wayside indication at the entrance of the signal block in which the cut section is included and may also give a false "proceed" indication in the locomotive equipment.

This happens when a train backs into the track circuit ahead of the cut which is producing continuous door bell code. Under such conditions relay FP remains energized.

- 5 To protect against the possibility of false controlling effects by "door bell" code, I propose to modify the basic back contact code receiving arrangement of Fig. 8 in the manner represented in Figs. 9 and 10. Referring to Fig. 9,
10 I have there represented a stretch of track 1—2 which includes a signal location X of the usual wayside type and which marks the entrance of a block including a cut section Xa, shown as being occasioned by an intersecting highway
15 10 with which the usual crossing protective signals XS are associated. Operation of these signals is controlled by a pair of interlocked relays XR1 and XR2 of the usual type.

Considering first the cut section equipment at
20 location Xa of Fig. 9, it is arranged to be used where the cut section is associated in the manner there shown with control facilities for highway crossing signals XS or is the starting point for approach locking of the character discussed
25 in connection with Fig. 3. Both front contact and back contact repeater relays FP and BP are controlled by contact 10 of the code following relay TR in a manner, before explained, which causes the contacts of relay BP to be
30 picked up only when relay TR responds to a trackway code.

This relay BP at location Xa is provided with contacts 44 and 47 which are respectively included in the circuits through which energy is supplied to the rails of track section X-Xa and over which the winding of interlocking relay XR2 is controlled. The latter circuit also includes a contact 71 of relay FP. The former is provided with facilities including a back point engageable by contact 44 for at times feeding steady energy to the rails of the rear track section X-Xa.

In operation of the cut section facilities shown at Xa in Fig. 9, coded energy received from the rails ahead of the insulated joints 3 produces code following response on the part of relay TR. This relay now maintains relays FP and BP picked up and, under the action of back contact 43, repeats coded energy into the rails of the track section to the rear of the mentioned joints. This energy is similar to the forward section code except that each "off" period thereof corresponds to the "on" period of that advance code and each "on" period of the rear section code corresponds to an "off" period of the forward code. When no energy is received by the relay TR, as in the event that the section ahead of location Xa is occupied, the contacts of all three of the relays TR, FP and BP are released and steady energy then is supplied to the rails of the rear section over a circuit which extends from supply terminal B through back contact 44 of relay BP, conductor 45 and the primary winding of track transformer TT back to supply terminal C.

Should one of the insulated joints 3 at location Xa break down, back contact 43 of relay TR would act (in absence of means for preventing such action), in the manner described in connection with Fig. 8 (i. e. when a train backs into the section of track of which the faulty joint marks the entrance), to produce the high frequency "door bell" code. In order to prevent this production I insert in the energizing circuit of back contact repeater relay BP a re-

actor 72 which is effective to cause relay BP to release its contacts whenever contact 10 of relay TR operates at the high frequency door bell rate which ordinarily approximates 8 cycles per second. One effect of such a release is to insure that the just traced steady energy or lock-out circuit will be established even though the high frequency door bell code which normally tends to hold relays FP and BP picked up, starts in the manner already explained.

The inserted reactor 72 is so dimensioned electrically that it has very little inductive effect upon currents of the low approach and clear code frequencies of 75 and 180 cycles per minute (one and one-fourth and three cycles per second, respectively). This assures that when relay TR responds to the approach code, the winding of relay BP will receive practically full normal energizing current and thus hold its contacts picked up during the longest "on" period of this approach or 75 code. Likewise, when the track relay TR operates in response to the 180 cycle per minute or 3 cycle per second code, the reactor 72 still presents only a comparatively small amount of impedance and thus does not reduce the intensity of energization of relay BP to a point where that relay is incapable of bridging the longest "on" period of the 180 code. Inasmuch as the length of this period is considerably less than that of the corresponding period of the 75 code, the somewhat lesser amount of energy received by the relay BP does not cause improper operation.

In the case, however, of the high frequency "door bell" code (which approaches 8 cycles per second), the reactor 72 offers such a considerably increased impedance to the flow of current that relay BP is incapable of picking up its contacts in response to this code. This increased impedance on the higher frequency is, of course, in accordance with the well-known variation of inductive reactance component thereof as the square of the frequency of the applied voltage. For example, the referred to tests show that at the door bell frequency of 8 cycles per second the impedance of reactor 72 is of the order of 6.4 as much as at the approach code frequency of one and one-fourth cycles per second. The same tests show that the cycles of this door bell code are approximately equal "on" and "off".

It will thus be seen that the use of reactor 72 in the manner represented in Fig. 9 assures that the door bell code will be ineffective for picking up relay BP and thus interfering with the desired operation of the steady energy or lock-out circuit of which back contact 44 of relay BP forms a part.

An equivalent result may be obtained by using the reactor in the modified manner indicated at 72a in Fig. 10. When this arrangement is used, both of the relays FP and BP will receive less than normal energy on the door bell code and hence neither one can then pick up. It should be noted that each of these two relays is so designed that it will hold its contacts picked up for a period which is just a little longer than the period of energization when there is no added impedance in the energizing circuit. Hence, if any considerable amount of impedance is inserted in that circuit, the relay will receive proportionately less energy and cannot under this condition hold its contact picked up for a time equal to the energizing period.

Considering next the equipment shown at 75

signal location **X** in Fig. 9, this form of apparatus organization is used where the section in advance of the signal **Sx** is at times fed steady energy for use in controlling highway crossing signals of the character shown at **XS**. It will be seen that this location **X** equipment is a modification of the basic apparatus organization represented at location **E** in Fig. 1. As here shown, moreover, the arrangement of the various devices which the organization at location **X** of Fig. 9 includes is similar to that disclosed and claimed in a copending application Serial No. 282,185 filed June 30, 1939 by Ralph R. Kemmerer on "Railway signaling systems". The two contacts **8** and **10** of the code following track relay **TR** respectively control operating circuits for code distinguishing relay **D180** and for the relays **FP**, **BP** and **H1**. Relay **H1**, in turn, will be seen to be controlled in a manner comparable to that discussed in connection with Figs. 4 and 6.

The control circuits for the three lamps of wayside signal **Sx** include contacts **21** and **22** of relays **H1** and **D180** arranged in the same manner as has been previously described in connection with the preceding figures. Likewise, the circuits through which alternating current source **B-C** supplies primary winding current to the track transformer **TT** connected to the rails of the track section in rear of location **X** are identical to the corresponding circuits of Figs. 4, 5 and 7 and closely comparable to the code selecting and "lock-out" circuits of Figs. 1 and 6. As will be seen, they include contacts **30**, **31** and **32** of the relays **FP**, **BP** and **H1** and contacts **75** and **180** of the coding device **CT**.

Interposed between relays **FP**, **BP** and **H1** and the code following contact **10** which controls these relays are a pair of auxiliary repeater relays **PFa** and **BPa** which are so arranged that relay **TR** must respond to two code periods (an "on" and an "off") before the three point pick-up circuits of relays **FP**, **BP** and **H1** are rendered effective. In other words, a total of five code periods must be responded to before code detecting relay **H1** picks up its contacts. This further delay is introduced to take care of certain conditions which involve the control of the highway crossing signals **XS**. The control in accordance with these conditions is effected through the medium of a contact **76** carried by relay **FPa** and included in the energizing circuit of crossing signal control relay **XR1**. Also included in this circuit is a line conductor **11**.

Further regarding the reasons for the further delay just mentioned, it is necessary in order that the steady energy which the facilities at cut section location **Xa** at times supply to the rails of track section **X-Xa** (to silence the crossing signals **SX**) will be ineffective for causing the lock-out circuit at location **X** to become active and thus repeat the energy into the track rails behind location **X** when both of the joints **3** at that location are performing their insulating function in the manner intended. The referred to five point pick-up action is effected by the apparatus of Fig. 9 in the following manner.

The first "on" period of trackway code initially responded to by relay **TR** at location **X** picks up relay **FPa** over a circuit which extends from the positive supply terminal through front contact **10** of relay **TR**, conductors **49** and **78**, back contact **79** of relay **FP**, conductor **81** and the winding of relay **FPa** back to the negative supply terminal. The following "off" period of the re-

ceived code picks up relay **BPa** over a circuit which extends from the positive supply terminal through back contact **10** of relay **TR**, door bell code protecting reactor **72**, conductors **73** and **13**, back contact **11** of relay **FP**, conductor **82**, front contact **83** of relay **FPa**, conductor **84**, and the winding of relay **BPa** back to the negative supply terminal. Relays **FPa** and **BPa** are made sufficiently slow releasing to bridge single periods of the trackway code. This delay may be provided in any suitable manner, as by use of snubbing resistors **85** and **86**.

The second "on" period of the trackway code to which relay **TR** responds picks up relay **FP** over a circuit which may be traced from the positive supply terminal through front contact **10** of relay **TR**, conductors **49** and **88**, front contact **89** of relay **BPa**, conductor **90**, back contact **91** of relay **H1**, conductor **12** and the winding of relay **FP** back to the negative supply terminal. 10 15 20

During the "off" period of the received trackway code which follows, contact **10** of relay **TR** picks up relay **BP** over a circuit which extends from the positive supply terminal through back contact **10**, reactor **72**, conductors **73** and **13**, front contact **11** of relay **FP**, conductor **14** and the winding of relay **BP** back to the negative supply terminal. 25

Finally, on the third "on" period of the received trackway code, relay **H1** is picked up over a circuit extending from the positive supply terminal through front contact **10** of relay **TR**, conductor **49**, back contact **50** of relay **H1**, conductor **52**, front contact **18** of relay **BP**, conductor **19** and the winding of relay **H1** back to the negative supply terminal. In response to this surge of heavy energization, relay **H1** completely picks up its contacts in the same manner as was explained in connection with the "back contact pick-up" action of Fig. 4 and locks itself in over a circuit which extends from the positive supply terminal through front contact **50** of relay **H1**, conductor **52**, front contact **18** of relay **BP**, conductor **19** and the winding of relay **H1** back to the negative supply terminal. 30 35 40 45

In picking up, contact **91** of relay **H1** interrupts the circuit over which the winding of relay **FP** received its initial pick-up energy. This interruption, however, does not cause relay **FP** to drop out for the reason that in picking up a contact **92** of relay **BP** set up another energizing path over which spaced pulses of current continue to flow to the winding of relay **FP**. The circuit for relay **FP** which is now active may be traced from the positive supply terminal through front contact **10** of relay **TR**, conductors **49** and **78**, front contact **79** of relay **FP**, conductor **83**, front contact **92** of relay **BP**, conductor **12** and the winding of relay **FP** back to the negative supply terminal. 50 55 60

For the purpose of modifying the response characteristics particularly in respect to the release delay period of relays **FP** and **BP** when the received trackway code is of the 75 pulse per minute frequency, the code distinguishing relay **D180** is provided with a pair of contacts **95** and **96**, which, at all times except when the relay is picked up in response to a reception of the 180 trackway code, connect a pair of resistors **97** and **98** in modifying relation with the snubbing circuits of the repeater relays **FP** and **BP**. When arranged in the manner shown, the effect of these resistors is comparable to that of the added resistor **54** which is included in the system of Fig. 4 in association with the repeater relay **BP**. 65 70 75

That is, the period of release delay of the relays FP and BP is extended during conditions of 75 trackway code reception over that which is effective during conditions in which the trackway code which operates relay TR has a frequency of 180 energy pulses per minute.

The various component parts of the signalling equipment shown in Fig. 9 having been described, attention will now be directed to the manner in which the apparatus of Fig. 9 operates. As long as the track stretch 1-2 is vacant, signal location apparatus (not shown) ahead of the cut section Xa supplies train control energy of the 180 code to the rails of the section of which Xa marks the entrance. At this location the facilities represented in Fig. 9 repeat this code into the rails of track section X-Xa. At signal location X, code following relay TR responds to this energy and causes all six of the relays controlled by contacts 8 and 10 to be continuously picked up. This causes wayside signal Sx to display the "clear" or green indication and the rails of the track section to the rear of location X to receive train control energy of the 180 coding.

As a train proceeds through the stretch of track represented in Fig. 9, the shunting action of its wheel and axles in entering section X-Xa deenergizes relay TR at location X and causes all six of the associated relays to release their contacts. In breaking the energizing circuit for relay XR1, contact 76 of relay FPa causes the highway crossing signals XS to be placed in operation by virtue of their operating circuits being completed at contact 99 or relay XR1. At location X, the wayside signal now shows the red or "stop" indication and the rails of the track section to the rear are supplied with energy of the 75 coding as a result of contacts 30 and 31 of relays FP and BP being released.

As the train advances beyond cut section location Xa it shunts relay TR at that location. This effects the release of relays FP and BP and contact 44 of relay BP now connects transformer TT continuously to the power source terminals B-C, thereby introducing steady energy into the rails of the track section X-Xa. As the rear of the train clears location Xa this steady energy is transmitted back to relay TR at location X.

In picking up, contact 10 of that relay completes the energizing circuit for relay FPa which in turn picks up and at contact 76 completes the circuit for highway signal control relay XR1. This relay picks up contact 99 and thereby discontinues operation of the crossing signals XS. This particular action is made possible because of the mechanical interlock (not shown) between contact 99 and companion contact 100 of relay XR2 which is arranged to prevent contact 100 from releasing as long as contact 99 is released and also after it is again picked up until such time as the winding of relay XR2 has again been energized.

The steady energy referred to above is ineffective, however, for picking up any of the relays FP, BP, H1 and D180 and for this reason, signal Sx continues to show "stop" and rails of the track section to the rear of location X continue to receive energy of the 75 coding as long as any portion of the train remains within the signal block of which location X marks the entrance.

When the rear of the train has cleared the end (not shown in Fig. 9) of this signal block, energy of the 75 coding is again received at loca-

tion Xa and repeated by the facilities there installed into the rails to the rear of this location. At the cut section, relays FP and BP are picked up and the energizing circuit for the winding of relay XR2 is completed over contacts 71 and 47 thereof. This restores the mentioned interlocking mechanism to a condition in which either contact 99 or 100 may be released to the highway signal operating position upon the deenergization of the associated relay winding.

At the signal location X, this 75 code energy effects pick up on the part of all five of the relays FPa, BPa, FP, BP and H1. Relay D180, however, still remains released. In consequence, the wayside signal Sx displays the yellow or "approach" indication and the track rails to the rear of location X receive energy of the 180 coding over a circuit which includes front contacts 30, 31 and 32 of relays FP, BP and H1.

In the event that the cut section apparatus at location Xa in Fig. 9 should not be provided with the door bell code eliminating reactor 72 (or 72a of Fig. 10) it is desirable that the signal location equipment to the rear of this cut section include provision for protecting against the undesirable effects of such door bell code which may be produced at the cut section and transmitted by the rails 1 and 2 to the track relay TR at location X. To this end, the signal location equipment under discussion is represented as including a reactor 72 connected in a manner equivalent to that shown at the cut section Xa.

The manner in which this reactor effects the desired protection is identical with that previously described in connection with the cut section description, namely, it offers such an increased impedance to the flow of current at the high "door bell" frequency as to make it impossible for relay BP to be picked up when the door bell code is received. In addition, auxiliary repeater relay BPa is also incapable of pick-up under the conditions stated for the reason that the reactor 72 also forms a part of its energizing circuit. This, of course, means that repeater relay FP must also remain released and in consequence a reception of the door bell code does not interfere with the supply to the rear track section of energy of the 75 coding over a circuit which includes back contact 31 of relay BP.

If desired, of course, the equipment at location X in Fig. 9 may also include the protective reactor connected in the manner shown at 72a in Fig. 10. In this case it would be impossible for door bell codes to pick up any of the relays in the group FPa-H1 for the reason that the reactor 72a is included in the pick-up circuit of each and every one.

Regarding the protection against broken down insulated joints at location X, the equipment of Fig. 9 operates in a manner which, for all practical purposes, is identical with that explained in connection with the earlier figures. Should such break-down occur and cause the coded energy supplied to the rear track section to be fed to the forward section track relay TR, the first "on" pulse of this energy picks up relay FPa, the following "off" period picks up relay BPa, the second "on" period picks up relay FP.

Contact 30 of relay FP now completes the lock-out circuit over which the rails of the rear section receive steady energy. In feeding over the defective joint this energy holds relay TR continuously picked up and thus prevents relay BP from responding. Both relays H1 and D180, in consequence, remain released and the signal Sx

displays the "stop" or red indication until the defective joint is repaired.

It will be noted that upon the expiration of the release period of relay BP_a , its contact 89 drops out and interrupts the pick-up circuit for relay FP . To prevent that relay from then also dropping out and interrupting the lock-out circuit, it is provided with a contact 106 which completes for the relay a "stick" circuit over 10 which the relay winding continuously receives energy as long as relay TR remains picked up. This stick circuit may be traced from the positive supply terminal through front contact 19 of relay TR , conductors 49 and 78, front contact 15 of relay FP , conductor 90 and the winding of relay FP back to the negative supply terminal.

Even though the door bell code protecting expedients of Figs. 9 and 10 have been disclosed 20 in an application involving alternating-current track circuit territory, it will be appreciated that these same expedients are also applicable to direct current track circuits where the direct current code-following track relay is connected directly 25 to the rails. In that situation, as in the one herein disclosed, the starting of door bell action at the cut section following the breakdown of both of the two insulated joints at that location initiates the same sequence of operations 30 that have been described in connection with Figs. 9 and 10 and prevents the giving of false signal indications in a manner which is the same as that explained herein for the application to alternating current track circuits.

35 A similar comment may be made relative to all of the improved features and forms of apparatus organization which form the subject matter of this application and which have been disclosed as forming parts of electrified territory installations. All are equally applicable to steam road 40 territory employing either alternating current or direct current track circuits and using track relays of any code following type in place of the single element designs herein shown.

45 From the foregoing it will be seen that I have provided new and improved forms of organizations of railway traffic controlling apparatus into signalling systems wherein coded energy normally is supplied at all times to the track circuits for 50 the purpose of controlling either or both wayside signals and train carried cab signals. All of these organizations are effective to prevent the controlled wayside signals from giving false "proceed" indications in the event of breakdown of 55 the insulated joints which electrically separate the rails of adjacent track sections.

This protection is effected without staggering the polarities of adjacent track circuits and without the necessity for use of two element track 60 relays. When brought into action, the protection facilities cause the wayside signal at the location of the defective joint to show "stop" even before the track block which is guarded by this signal becomes vacated and in addition the facilities operate to continue this "stop" indication 65 uninterrupted until the broken down joint is repaired.

Moreover, the facilities are so arranged that should the supply of steady lock-out energy which 70 feeds over the defective joint be momentarily interrupted, the protection above discussed will automatically restore itself without producing even a temporary "approach" or "clear" indication on the part of the affected wayside signal. 75 Failure of the facilities as a result of accidental

improper operation of the relay contacts and the conductors which are included in my improved lock-out circuits is also effectively guarded against.

I have also provided cooperating cut section 5 facilities which are effective to break up cascading action of the steady track circuit energy which is used under lockout conditions, to detect and prevent undesired false operating effects of a breakdown of the insulated rail joints at the 10 cut section location, and to take care of the conditions which the presence of high frequency "door bell" codes introduce.

In connection with the above, I have provided improved recoding facilities for controlling the 15 wayside signals and for selecting the coding of the energy which is supplied to the track circuits. Still more important, I have accomplished all of the above without dispensing with any of the desirable features of continuously coded track 20 circuits.

Although I have herein shown and described only a comparatively few of the many possible forms of railway traffic controlling apparatus embodying my invention, it is understood that 25 various changes and modifications may be made therein within the scope of the appended claims without departing from the spirit and scope of my invention.

Having thus described my invention, what I 30 claim is:

1. In combination with adjoining forward and rear sections of railway track which are electrically separated by insulated rail joints, means for supplying coded energy to the rails of said forward section, a code following track relay operated by energy received from said rails, a first slow release relay energized when said track relay is picked up, a second slow release relay energized when said track relay is released provided 40 said first slow release relay is picked up, a signal positioned at the entrance of said forward section, means including said track and slow release relays for controlling said signal in such manner that it displays a permissive indication when the 45 track relay is following code and a restrictive indication when the track relay is either picked up or released continuously, an energizing source for said rear track section, a coding contact, a circuit completed over a back contact of said section slow release relay only for connecting said rear section rails to said energizing source over 50 said coding contact, and a circuit completed over a front contact of said first slow release relay and a back contact of said second slow release 55 relay and effective to connect said rails directly to said energizing source in the event that energy should feed over said insulated rail joints from the rear track section into the forward section.

2. In combination with adjoining forward and rear sections of railway track which are electrically separated by insulated rail joints, means for supplying coded energy to the rails of said forward section, a code following track relay operated by energy received from said rails, a first 60 slow release relay energized over a front contact of said track relay, a second slow release relay energized over a back contact of the track relay and a front contact of said first slow release relay, a code detecting relay energized when said 65 second slow release relay is picked up and deenergized when that relay is released, a signal positioned at the entrance of said forward section and controlled by said code detecting relay in a manner that it displays "proceed" when 70 75

that relay is picked up and "stop" when that relay is released, an energizing source for said rear track section, a coding contact, a circuit completed over a back contact of said second

- 5 slow release relay only for connecting said energizing source to the rails of said rear section over said coding contact whereby when said first and second slow release relays are both released to supply those rails with energy that is periodically interrupted, and a circuit completed when said first slow release relay is picked up and said second slow release relay is released and including front and back contacts of those two relays respectively for connecting said energizing source
- 10 directly to said rear section rails whereby should said insulated rail joints break down then to supply those rear section rails with energy that is uninterrupted and that in leaking over the joints into said forward section rails holds said
- 15 20 track relay continuously picked up and thereby causes said code detecting relay to put said signal at "stop."

3. In combination with adjoining forward and rear sections of railway track which are electrically separated by insulated rail joints, means for supplying the rails of said forward section with energy coded at a first rate under certain conditions and at a second rate under other conditions, a code following track relay operated by energy received from said forward section rails, a code distinguishing relay controlled by said track relay and responsive to trackway energy of said first code rate only, a first slow release relay energized over a front contact of said track relay, a second slow release relay energized over a back contact of the track relay and a front contact of said first slow release relay, a code detecting relay energized when said second slow release relay is picked up and deenergized when that relay is released, a signal positioned at the entrance of said forward section and controlled by said code detecting and code distinguishing relays in a manner that it displays "stop" when the code detecting relay is released, an energizing source for said rear track section, first and second coding contacts which operate at different speeds, a circuit completed over a front contact of each of said slow release and code detecting relays for connecting said energizing source to the rails of said rear section over said first coding contact whereby to supply those rails with energy that is periodically interrupted at a first rate, a circuit completed over a back contact of said second slow release relay only for connecting said source to said rear section rails over said second coding contact whereby to supply those rails with energy that is periodically interrupted at a second rate, and a circuit completed over a front contact of said first slow release relay and a back contact of the second slow release relay for connecting said energizing source directly to said rear section rails whereby should said insulated rail joints break down then to supply those rear section rails with energy that is uninterrupted and that in leaking over the joints into said forward section rails holds said track relay continuously picked up and thereby causes said code detecting relay to put said signal at "stop".

4. In combination with adjoining forward and rear sections of railway track; means for supplying the rails of said forward section with coded energy; a code following track relay operated by energy received from said forward section rails; a decoding transformer energized over front and back contacts of said track relay; first and second

slow release relays controlled by said track relay and responsive to the first "on" period and to the following "off" period respectively of each series of trackway energy pulses which the track relay receives; a code detecting relay; a circuit effective to supply pick-up current to said code detecting relay during the second "on" period of each of said received series of energy pulses and which includes a reverse current blocking rectifier, a front contact of said second slow release relay and the said front contact of the track relay over which said decoding transformer is energized; a circuit effective after the code detecting relay has picked up to supply stick current to that relay and which includes a front contact of that relay and said front contact of the second slow release relay; and means controlled by said code detecting and repeater relays for supplying energy to the rails of said rear track section.

5. In combination with adjoining forward and rear sections of railway track which are electrically separated by insulated rail joints, means for supplying coded energy to the rails of said forward section, a code following track relay operated by energy received from said forward section rails, a first slow release relay energized over a front contact of said track relay, a second slow release relay energized over a back contact of the track relay and a front contact of said first slow release relay, a code detecting relay picked up over front contacts of said track and second slow release relays during the second "on" period of each of said received series of energy pulses and held picked up by stick current supplied over a front contact of that relay and a front contact of the second slow release relay, an energizing source for said rear track section, first and second coding contacts which operate at different speeds, a circuit completed by front contacts of said code detecting and slow release relays for connecting said energizing source to the rails of said rear section over said first coding contact whereby to supply those rails with energy that is periodically interrupted at a first rate, a circuit completed over a back contact of said second slow release relay only for connecting said source to said rails over said second coding contact whereby to supply those rails with energy that is periodically interrupted at a second rate, a circuit completed by a front contact of said first slow release relay and a back contact of the second slow release relay for connecting said energizing source directly to said rear section rails whereby should said insulated rail joints break down then to supply those rear section rails with energy that is uninterrupted and that in leaking over the joints into said forward section rails holds said track relay continuously picked up, and a signal which governs the entry of traffic into said forward section and which is controlled by said track relay in a manner to show "proceed" when that relay follows code and "stop" when that relay is stationary either in its said picked-up position or in its released position.

6. In combination with adjoining forward and rear sections of railway track which are electrically separated by insulated rail joints, a source of coded energy and a code following track relay connected with the rails of said forward section, a first slow release relay energized over a front contact of said track relay, a second slow release relay energized over a back contact of the track relay and a front contact of said first slow release relay, an energizing source for said rear track

section, a coding contact, a circuit completed by a back contact of said second slow release relay only for connecting said energizing source to the rails of said rear section over said coding contact 5 whereby to supply those rails with energy that is periodically interrupted, a circuit completed by the said back contact of said second slow release relay and a front contact of said first slow release relay for connecting said energizing source 10 directly to said rear section rails whereby should said insulated rail joints break down then to supply those rear section rails with energy that is uninterrupted and that in leaking over the joints into said forward section rails holds said track 15 relay continuously picked up, and a signal which governs the entry of traffic into said forward section and which is controlled by said track relay in a manner to show "proceed" when that relay follows code and "stop" when that relay is stationary either in its said picked-up position or in its released position.

7. In combination with adjoining forward and rear sections of railway track which are electrically separated by insulated rail joints, means 25 for supplying coded energy to the rails of said forward section, a code following track relay operated by energy received from said forward section rails, first and second slow release relays energized over front and back contacts respectively of said track relay and respectively arranged to pick up during the first "on" period and during the following "off" period of each received series of recurring pulses of coded trackway energy, an energizing source for said rear 30 track section, a coding contact, a circuit completed by a back contact of said second slow release relay only for connecting said source to the rails of said rear section over said coding contact whereby to supply those rails with energy 35 that is periodically interrupted, a circuit completed by the said back contact of said second slow release relay and a front contact of said first slow release relay for connecting said energizing source directly to said rear section rails 40 whereby should said insulated rail joints break down then to supply those rear section rails with energy that is uninterrupted and that in leaking over the joints into said forward section rails holds said track relay continuously picked up, 45 and a signal which governs the entry of traffic into said forward section and which is controlled by said track relay in a manner to show "proceed" when that relay follows code and "stop" when that relay is stationary either in its said 50 picked-up position or in its released position.

8. In combination with adjoining forward and rear sections of railway track which are electrically separated by insulated rail joints, a source of coded energy and a code following track relay connected with the rails of said forward section, a first slow release relay energized when said track relay is picked up, a second slow release relay energized when said track relay is released provided said first slow release relay is 60 picked up, a code detecting relay energized when said second slow release relay is picked up, an energizing source for said rear track section, first and second coding contacts which operate at different speeds, a circuit completed when said code detecting relay and both of said slow release relays are picked up for connecting said energizing source to the rails of said rear section over said first coding contact whereby to supply those rails with energy that is periodically interrupted 65 at a first rate, a circuit completed over a back

contact of said second slow release relay only for connecting said source to said rear section rails over said second coding contact when said second slow release relay is released whereby to supply those rails with energy that is periodically interrupted at a second rate, a circuit completed when said first slow release relay is picked up and said second slow release relay is released and including front and back contacts of those two relays respectively connecting said energizing source directly to said rear section rails whereby should said insulated rail joints break down then to supply those rear section rails with energy that is uninterrupted and that in leaking over the joints into said forward section rails holds said track relay continuously picked up, and a signal which governs the entry of traffic into said forward section and which is controlled by said track relay in a manner to show "proceed" when that relay follows code and "stop" when that relay is stationary either in its said picked-up position or in its released position.

9. In combination with adjoining forward and rear sections of railway track which are electrically separated by insulated rail joints, means 25 for supplying coded energy to the rails of said forward section, a code following track relay connected to said rails and operated by energy received therefrom, three decoding relays controlled by said track relay and arranged to pick up sequentially in respective step with the first three periods of each received series of recurring pulses of trackway energy, an energizing source for said rear track section, first and second coding contacts which operate at different speeds, a circuit completed over a front contact of each of said three decoding relays for connecting said energizing source to the rails of said rear section over said first coding contact whereby to supply those rails with energy that is periodically interrupted at a first rate, a circuit completed over a back contact of said second decoding relay only for connecting said source to said rear section rails over said second coding contact whereby to supply those rails with energy that is periodically interrupted at a second rate, a circuit completed over a front contact of said first decoding relay and a back contact of said second decoding relay for connecting said energizing source directly to said rear section rails 30 whereby should said insulated rail joints break down then to supply those rear section rails with energy that is uninterrupted and that in leaking over the joints into said forward section rails holds said track relay continuously picked up, 35 and a signal which governs the entry of traffic into said forward section and which is controlled by said track relay in a manner to show "proceed" when that relay follows code and "stop" when that relay is stationary either in its said picked-up position or in its released position.

10. In combination with adjoining forward and rear sections of railway track which are electrically separated by insulated rail joints, a source of coded energy and a code following 40 track relay connected with the rails of said forward section, first and second slow release relays controlled by said track relay and arranged to respond to the first "on" period and to the following "off" period respectively of each received series of coded trackway energy pulses, a code detecting relay controlled by said track and slow release relays and arranged to respond to the second "on" period of each of said received series of recurring energy pulses, an energizing source directly to said rear section rails whereby should said insulated rail joints break down then to supply those rear section rails with energy that is uninterrupted and that in leaking over the joints into said forward section rails holds said track relay continuously picked up, 45 and a signal which governs the entry of traffic into said forward section and which is controlled by said track relay in a manner to show "proceed" when that relay follows code and "stop" when that relay is stationary either in its said picked-up position or in its released position.

gizing source for said rear track section, first and second coding contacts which operate at different speeds, a circuit completed over a front contact of each of said code detecting and two slow release relays for connecting said energizing source to the rails of said rear track section over said first coding contact whereby to supply those rails with energy that is periodically interrupted at a first rate, a circuit completed over a back contact of said second slow release relay only for connecting said source to said rear section rails over said second coding contact whereby to supply those rails with energy that is periodically interrupted at a second rate, a circuit completed over a front contact of the first slow release relay and a back contact of the second slow release relay for connecting said energizing source directly to said rear section rails whereby should said insulated rail joints break down then to supply those rear section rails with energy that is uninterrupted and that in leaking over the joints into said forward section rails holds said track relay continuously picked up, and a signal which governs the entry of traffic into said forward section and which is controlled by said track relay in a manner to show "proceed" when that relay follows code and "stop" when that relay is stationary either in its said picked-up position or in its released position.

11. In combination with adjoining forward and rear sections of railway track which are electrically separated by insulated rail joints, means for supplying coded energy to the rails of said forward section, a code following track relay operated by energy received from said rails, a first slow release relay energized over a front contact of said track relay, a second slow release

relay energized over a back contact of the track relay and a front contact of said first slow release relay, a delayed responding code detecting relay energized over a front contact of said second repeater relay, an energizing source for said rear track section, first and second coding contacts which operate at different speeds, means including front contacts of said slow release and code detecting relays and responsive to code following operation of said track relay for connecting said energizing source to the rails of said rear track section over said first coding contact whereby to supply those rails with energy that is periodically interrupted at a first rate, means including a back contact of said second slow release relay and effective when said track relay is continuously released for connecting said source to said rear section rails over said second coding contact whereby to supply those rails with energy that is periodically interrupted at a second rate, means including said back contact of the second slow release relay and said front contact of the first slow release relay and effective when said track relay initially picks up for connecting said source directly to said rear section rails whereby should said insulated rail joints break down then to supply those rear section rails with energy that is uninterrupted and that in leaking over the joints into said forward section rails holds said track relay continuously picked up, and a signal which governs the entry of traffic into said forward section and which is controlled by said track relay in a manner to show "proceed" when that relay follows code and "stop" when that relay is stationary either in its said picked-up position or in its released position.

HOWARD A. THOMPSON.
